UNITED STATES PATENT OFFICE.

HENRY J. HEINZ, OF PITTSBURG, PENNSYLVANIA.

DESIGN FOR A BOTTLE.

SPECIFICATION forming part of Design No. 32,917, dated July 10, 1900.

Application filed May 10, 1900. Serial No. 16,238. Term of patent 14 years.

To all whom it may concern:

Be it known that I, HENRY J. HEINZ, a citizen of the United States, residing at Pittsburgh, in the county of Allegheny and State of Pennsylvania, have invented and produced a certain new and original Design for Bottles, of which the following is a specification.

Figure 1 is a side elevation of a bottle, showing my new design; and Fig. 2 is a sectional view on the line II II, Fig. 1.

As shown in the drawings, the leading or material feature of my design consists in a configuration of bottle which may be defined as "flagon-shaped" or "pear-shaped"—i. e., a bottle having a bulging body which tapers into a relatively-long neck—the bottle being divided longitudinally into panels 1 by a

number of ribs 2, which give a roughly-polygonal shape to the bottle in cross-section. The panels which are included between these 20 ribs are curved transversely as well as vertically, as is clearly shown in the drawings.

Having described my invention, what I claim as new, and desire to secure by Letters Patent, is—

The design for a bottle, as herein shown and described.

In testimony whereof I have hereunto set my hand.

HENRY J. HEINZ.

Witnesses:

H. H. COWAN,
E. D. McCAFFERTY.
